[57] CLAIM

The ornamental design for a pinkered ribbon print form, as shown and described.

DESCRIPTION

FIG. 1 is a perspective view of my new design of a "pinkered" ribbon print form;

FIG. 2 is a front view of the pinkered ribbon print form shown in FIG. 1;

FIG. 3 is a right side view of the pinkered ribbon print form shown in FIG. 1, the left side view being identical thereto; and,

FIG. 4 is a top plan view of the pinkered ribbon print form shown in FIG. 1, the bottom being identical thereto.

The dash lines shown on the front surface of the pinkered ribbon print form represent fold lines and the broken line showing of written indicia is for illustrative purpose only and forms no part of the claimed design.

The surfaces or portions of the article not shown in the drawing or described in the specification forms no part of the claimed design.
